UNITED STATES PATENT OFFICE.

WILLIS A. SMITH, OF CAPE NEDDICK, MAINE.

SIGN-HOLDER.

1,033,838.

Specification of Letters Patent. Patented July 30, 1912.

Application filed March 14, 1912. Serial No. 683,822.

To all whom it may concern:

Be it known that I, WILLIS A. SMITH, a citizen of the United States, residing at Cape Neddick, in the county of York and State of Maine, have invented certain new and useful Improvements in Sign-Holders, of which the following is a specification, reference being had to the accompanying drawings.

10. This invention relates to improvements in sign holders and more particularly to a sign holder whereby one or a plurality of signs can be quickly and readily mounted and changed as desired.

15. Another object of the invention is to provide a sign holder of this character which will possess advantages in points of efficiency and durability, is inexpensive of manufacture and at the same time simple in 20 construction and operation.

With the above and other objects in view the invention consists of the novel features of construction, combination and arrangement of parts as will be hereinafter more 25 fully described, pointed out in the claims and shown in the accompanying drawings, in which—

Figure 1 is a front elevation of a sign holder constructed in accordance with my 30 invention; Fig. 2 is a side elevation; Fig. 3 is a sectional view on the line 3—3 of Fig. 1. Fig. 4 is a sectional view on the line 4—4 of Fig. 1. Fig. 5 is a side elevation showing a slightly modified form.

35. Referring more particularly to the drawings, 1 indicates a base member preferably formed of galvanized sheet metal, but any other suitable material may be used if desired. Mounted upon the base and having 40 their ends suitably secured are the spaced guide rods 2. Slidably mounted upon the guide rods are the spacing plates 3, said plates being formed of metal and bent upon themselves to form the channel 4, in which 45 is disposed a retaining plate 5, adapted to abut against the edges of a sign and hold the same against longitudinal movement.

Bowed spring members 6 are arranged within the spacing plates, having their ends 50 engaging the intermediate portion of the plate, the intermediate portion of said springs bearing against the retaining plates to yieldingly engage said retaining plates with the base member. Flanges 7 are 55 formed on the longitudinal edges of the spacing plate adapted to be disposed over

the edge of a sign and hold the same in position against the base. The spacing plates 3 are provided at their ends with the openings 8 adapted to receive the guide rods 2 60 whereby the plates are slidably mounted on the guide rods and can be arranged in any desired position. Each end of the base member is bent upon itself to form a channel 9, adapted to receive the edge of a sign 65 when the same is arranged upon the base member.

In Fig. 5 I have shown a slightly modified form of construction wherein the base member is formed of wood instead of metal. 70 When the base member is constructed of wood I provide a metal plate 10 adapted to be secured to the ends of the base and having one of its longitudinal edges bent upon itself as shown at 11, to form a channel 12 75 adapted to receive the edges of a sign.

In placing the sign in position upon the base member, beginning at the end of the base, the upper edge of the sign is arranged within the channel 12 and the spacing plate 80 is then moved toward the upper end of the sign until the retaining plate engages the lower edge of the sign to hold the same against longitudinal movement, and the flange 7 will be arranged above the edge of 85 the sign to hold the same in position against the base. To remove the sign the lower spacing plate is pushed outwardly toward the lower end of the base to remove the lowermost sign, the rest can be removed by 90 pushing the spacing plates toward the lower end of the base.

From the above description taken in connection with the accompanying drawings it 95 will be readily seen that I have provided means whereby one or a plurality of signs can be quickly mounted and changed as desired.

While I have shown and described the preferred form of my invention it will be obvious that various changes in the details of construction and in the proportions may be resorted to within the scope of the claims for successfully carrying the invention into practice without sacrificing any of the novel 100 features or departing from the spirit thereof.

Having thus fully described this invention, what is claimed is:—

1. A sign holder comprising a base member, spaced guide rods mounted on said base 110 member, spacing plates slidably mounted on said guide rods, retaining plates carried by

the spacing plates and yieldingly engaging the base to prevent longitudinal movement on a sign.

2. A sign holder comprising a base member, having its ends bent upon itself to form channels to receive the edge of a sign, spaced guide rods mounted on said base, spacing plates slidably mounted on the guide rods, retaining plates carried by said spacing plates and a bowed spring arranged in the spacing plates and disposed between the intermediate portion of the spacing plates to hold the retaining plates in yielding engagement with the base member to prevent longitudinal movement of the sign.

3. A sign holder comprising a base member, spaced guide rods mounted on said base member, having their ends fixed thereto, spacing plates slidably mounted on said

guide rods, said plates comprising a single 20 piece of sheet metal bent upon itself to form a channel, a retaining plate disposed within said channel, a bowed spring member disposed in the channel and arranged between the retaining plate and the intermediate portion 25 of the spacing plates to yieldingly hold the retaining plates against the base to prevent longitudinal movement of a sign, upwardly extending flanges formed on the edges of the spacing plate adapted to hold 30 the sign in position against the base.

In testimony whereof I hereunto affix my signature in the presence of two witnesses.

WILLIS A. SMITH.
